UNITED STATES PATENT OFFICE

WALTER F. STIMPSON, OF LOUISVILLE, KENTUCKY

SCALE

Application filed August 27, 1923. Serial No. 659,625.

The invention relates to scales and consists in various features of construction as hereinafter set forth.

In the drawings:

- 5 Figure 1 is a front elevation of the scale;
- Figure 2 is a sectional elevation of the upper portion of the column;
- Figure 2^a is an enlarged detail of a portion of Figure 2;
- 10 Figure 3 is a sectional elevation of the lower portion of the column and the platform;

Figure 3^a is an enlarged detail of a portion thereof;

- 15 Figure 4 is a sectional side elevation of the base portion of the scale;

Figure 5 is a horizontal section through the lower portion of the column;

- 20 Figure 6 is a sectional plan view of the upper portion of the column;

Figure 7 is a perspective view of the base with the platform partly removed;

- 25 Figures 8 and 9 are diagrammatic views illustrating respectively in plan and sectional side elevation the operation of the chart shifting mechanism;

Figures 10, 11, 12 and 13 are similar views showing different positions of adjustment.

The general type of scales to which my improvements are particularly applicable is that known as "automatic", and in which the variable weighing force is produced by the deflection of a pendulum weight. One of the features of the invention is the construction 30 of this pendulum weight and the means by which it may be easily and accurately adjusted to compensate for any "slowing" or inaccuracy due to wear.

Another feature is the construction of the 40 indicating mechanism and the means by which the indices are automatically changed upon the addition of weights.

Still another feature is the construction 45 of a tiltable beam frame which forms in effect a cap for the hollow supporting column.

Other features are the platform frame, the 50 platform and associated parts, which are so constructed as to secure low cost of manufacture, and various advantages which will be specifically referred to.

In the construction of platform scales, it is usual to provide an annular base frame formed of cast metal and enclosing the platform levers upon which the platform is supported. A hollow column rises from one end of the base frame and the weighing and indicating mechanism is mounted within and upon this column. With my improved construction the base frame is of skeleton construction and the platform is provided with 55 depending flanges for enclosing the frame and excluding dirt.

In detail, the base frame is preferably formed of angle bars A and B bent into annular form and connected by vertical struts C to form a Z-beam having an outwardly extending base flange D and an inwardly extending top flange D'. At one end this frame is preferably rounded and the connecting strut C' is continuous to close the space between the angle bars. Above this portion the hollow column F is mounted, this being provided with a foot portion G that forms a cap or closure for the top of the frame. Within the frame are platform levers H and 60 I of usual construction which support a platform frame J having depending feet K. The platform L is preferably formed of pressed sheet metal and is provided with depending skirt flanges M at the sides and one end for 65 overlapping and enclosing the skeleton frame. It is further preferably provided with a central reinforcing bar L' secured to its under side, the stem portion of which is engageable with notched bearings L² at opposite ends of 70 the frame J. This also serves as a positioning means for retaining the platform from lateral displacement. Thus the structure as just described is one which is exceedingly 75 light and inexpensive to manufacture and the outwardly extending base flange G acts as a guard preventing any contact with the platform which might interfere with its freedom.

To permit of transporting the scale, it is usual to provide a wheel base with one or 80 more swiveled castor wheels. With my improved construction these swiveled castor wheels are mounted upon the base G of the hollow column, projecting downward therefrom and enclosed within the portion C' of 85 100

the frame. In detail, the base G is provided with depending bosses G' bored for the passage of the shank N of the castor wheel bracket N', an anti-friction thrust bearing N² being arranged between this bracket and the boss and the wheel N³ being journaled in the bracket. This avoids the necessity of providing other attachment fittings for the castors and simplifies the construction of the base frame.

10 The hollow column F is preferably provided at its upper end with a flaring or fan-shaped portion F' upon which is mounted the beam frame O. This is preferably a casting forming in effect a cap for the column, being provided with depending skirt flanges O' which overlap and are slightly spaced from the walls of the column. The frame is centrally fulcrumed upon the column by inwardly projecting knife edge bearings P which engage V bearing blocks P' located in recesses in the opposite walls of the column. Upwardly projecting posts O² are arranged at opposite ends of the frame O and the tare-beam O³ having the shiftable poise O⁴, is mounted upon these posts. There is also a portion O⁵ which extends centrally of the beam frame and holds the scale or chart for cooperating with the index hand. Thus the frame O performs the several functions of a cap for the column, a beam and an indicator chart carrying frame.

15 The beam frame O is connected with the platform levers by the steelyard rod Q, the upper portion of which is bifurcated and is provided with bearing loops Q' for engaging inwardly extending knife edge bearings Q². These knife edge bearings Q², as well as the knife edge bearings P, are attached to the frame O and for convenience in so attaching they are directly secured to plates Q³ detachably connected to opposite sides of the frame O. The sides of the frame O are cut away to provide clearance for the passage of these pivots and the plates Q³ are screwed or otherwise secured to the frame so as to be normally rigid therewith.

20 The indicating mechanism comprises an arm R secured to and depending from the beam frame O on one side of the fulcrum and within the hollow column F. Near the lower end of this arm is a pivot bearing R' for the index hand R², which extends upward and has its upper end exposed to view within the portion O⁵. The hand R² extends downward below the pivot R' and is connected by a check link S to an anchor bearing, forming, in effect, a fulcrum about which the hand turns. Provision is made for adjusting the radial distance between the pivot R' and the link S, this comprising bearing members S' and S² with which the opposite ends of the link have knife-edge pivotal engagement. These bearing members in turn are supported by center bearings S³ and S⁴, the one slidably engaging

25 a socket and being yieldably pressed by a spring S⁵ and the other having a threaded engagement with its socket by which it may be adjusted vertically. The bearing S' is secured as just described to the index hand R, while the bearing S² is similarly secured to a bracket member S⁶ secured to the column F. The construction is such that by adjusting the threaded center members S⁴, the opposite ends of the link S may be raised or lowered, thereby changing the radial length between the pivot R' and the link without altering the angular relation of the latter to the index hand.

30 It is usual to provide automatic indicator scales with additional weights for increased weighing capacity. To automatically change the indicating mechanism when such weights are used, I have devised the following construction:

35 T is a member secured at the center of the beam frame O and providing a bearing with a vertically extending pivot T' for engaging one or more auxiliary weight arms T². The free ends of these weight arms are engageable with latch bearings T³ and T⁴ on opposite ends of the beam so that by swinging the arms the weights may be shifted from one end of the beam to the other. U is a segmental chart or indicator scale within the portion 40 O⁵ of the beam frame and adjacent to the index hand R. This is preferably bifurcated and has markings upon the reverse sides so that a reading may be taken either from the front or the back of the scale. Adjacent to each of these markings there is a window or opening U' through which there is exposed an inner shiftable scale member U². This inner member is longitudinally slidable and is connected by a linkage to the weight members T². The arrangement is such that the swinging of either one or more of the weight members from one end of the beam to the other will effect the automatic adjustment of the member U² so as to expose additional numerals through the windows U'. This will change the indicated weight to correspond to the shifting of weights on the beam. Any suitable linkage may be used for this purpose, but as shown the individual weight arms 45 T² are connected with eccentrics T⁵ and T⁶, which are connected to an even lever T⁷ centrally pivotally attached to the member U². Thus where only one of the weights is swung, the adjustment of the member U² will be sufficient to expose one set of numerals through the windows U', while the swinging of the second weight will effect a further adjustment, exposing a different set of numerals, as shown in Figures 8 to 13.

50 The steelyard rod Q is preferably connected to the platform levers through an intermediate lever V controlled by a dash-pot V' and it is also connected through the medium of a yoke V² and links V³ and V⁴ with op- 55

positely swinging pendulum weights W and W' . It has been found that after a scale has been in use, it loses its sensitiveness and accuracy of indication, due doubtless to the slight wear in the knife-edge pivots and other parts. Therefore, it is necessary from time to time to adjust the pendulum weights to compensate for this "slowing" of the scale. The amount of adjustment necessary is, however, so slight that it is difficult to accomplish the desired result by shifting of the main ball of the pendulum weight and particularly where a pair of oppositely swinging pendulums are used it is difficult, when adjusting, to maintain perfect balance between the two. This difficulty I have overcome by providing each of the pendulum weights with a small ball or adjustable weight in addition to the main or large ball. In detail, each of the pendulum weights W and W' is provided with a main ball W^2 and at one side thereof an auxiliary ball W^3 which is mounted on a threaded stem W^4 . The ratio between the weights W^2 and W^3 is such that an adjustment of the latter has but slight effect in altering the total weight, and therefore a very fine adjustment may be made to compensate for slight changes.

With the construction as described, in operation, when a load is placed upon the platform L the platform levers will be depressed and through the connections described, will deflect the pendulum weights W and W' oppositely until a balance is attained. At the same time, the steelyard rod Q will rock the beam frame O upon the pivot P , which in turn will swing the arm R . As has been described, the lower end of this arm R is pivotally connected to the pivot bearing R' for the index hand R^2 , which is also connected to the check link S . The normal position of the parts when the platform is unloaded is such that the index hand is at the zero end of the scale, but upon the tilting of the frame O this hand will be swung towards the opposite end until the position of balance is reached. This will indicate the exact weight of the load on the platform unless the load is beyond the weighing capacity of the scale without additional weights. In such case one of the weighted arms T^2 is swung from its normal position through a half revolution, where it will be arranged at the opposite end of the beam, as indicated in the diagrammatic views in Figures 10 and 11. Such movement will rock the even lever T' , which, through its connection with the inner chart U^2 , will shift the latter until one series of numerals is registered with the window openings U' in the indicator chart U . As a result the reading of the chart is altered to add the weight of the shiftable weight arm T^2 . If the load is beyond the capacity of the scale with a single weight T^2 , the second weight may be swung in the manner described, the parts be-

ing in the position indicated in Figures 8 and 9. In this position the movement of both eccentrics will double the throw of the lever T' , thereby registering a second series of numerals with the window openings U' .

It is advantageous to take a reading from either front or back of the scale and with certain constructions heretofore used double index hands have been employed for this purpose. With my construction the single index hand R^2 is used for front and back, being arranged directly beneath the chart members U and U^2 and exposed in an opening through the frame O . Thus all positions of adjustment of the hand are equally visible from front and rear of the scale and the point of the hand is of sufficient width to be adjacent to the indices on said scale in front and rear.

The mechanical construction of the parts is such as to secure lightness, strength and durability, while the arrangement of the castor wheels insures stability and ease in transportation to different positions on the floor.

What I claim as my invention is:

1. In a scale, the combination with a platform, of platform supporting levers, a pedestal and weighing mechanism mounted thereon and connected with said platform levers, of a skeleton base frame on which said pedestal is mounted enclosing said platform levers and a skirt depending from said platform to enclose said skeleton frame.

2. In a scale, the combination of a skeleton base frame and a platform having a depending skirt for enclosing said frame.

3. In a scale, the combination with a cast metal skeleton pedestal, of a wrought metal base frame on which said pedestal is mounted, platform supporting levers within said frame and a platform having a depending skirt for enclosing said frame and levers.

4. In a scale, the combination with a cast metal pedestal provided with an integral foot portion, of a skeleton wrought metal base frame upon which the foot portion of said pedestal is mounted, platform levers within said frame and a platform having a depending skirt enclosing said skeleton frame.

5. In a scale, the combination with a cast metal pedestal having a foot portion, of a base frame on which said pedestal is mounted, said base frame formed of wrought metal and comprising spaced top and bottom annular sections and connecting struts therebetween.

6. In a scale, a base frame formed of upper and lower angle bars and struts connecting the same, the vertical flanges of said angle bars being in alignment and the horizontal flanges projecting respectively inward and outward.

7. In a scale, a base frame comprising upper and lower annular frame sections of angle cross section, the vertical flanges thereof being in alignment and the lateral flanges projecting respectively inward and outward,

and spaced struts connecting said upper and lower frame portions.

8. In a scale, a base frame comprising spaced upper and lower annular members of angle bar cross section, a strip connecting the vertical flanges of said section extending around a portion of the frame, a pedestal supported on a portion connected by said strip, a platform supported on levers within said frame and a depending skirt on said platform overlapping said frame and concealing the portion unenclosed by said strip.

9. In a scale, a base frame having a skeleton portion and a platform supported on levers within said frame provided with a depending skirt for enclosing said skeleton portion.

10. In a scale, a base frame formed with a skeleton portion and an enclosed portion, a pedestal mounted on the enclosed portion, and a platform above the skeleton portion supported on levers within the same and provided with a depending skirt for enclosing the same.

11. In a scale, a base frame formed of upper and lower annular sections including a substantially rectangular portion and a rounded end portion, a strip connecting said sections in the rounded end portion thereof, a pedestal mounted on said end portion and provided with a foot for covering the same, a platform above the rectangular portion supported on levers within the frame, and a depending skirt on said platform for enclosing the portion uncovered by said strip.

12. In a scale, a base frame having an outwardly extending flange at the bottom thereof and a platform supported on levers within said base frame having a depending skirt overlapping and spaced from the side walls of said frame and within the dimensions of said flange.

13. In a scale, a skeleton base frame provided with an outwardly extending flange at the bottom thereof, a platform supported on levers within said base frame having a depending skirt overlapping and spaced from the skeleton sides of said base frame and within the dimensions of said outwardly extending flange.

14. In a scale, a skeleton frame having an end portion thereof enclosed, a pedestal mounted on the enclosed portion provided with a laterally extending foot portion for covering the same, a platform supported on levers within said frame overlapping said foot portion, and a skirt depending from said platform enclosing the sides of said skeleton portion and overlapping the sides of the enclosed portion.

15. In a scale, the combination with a skeleton base frame and a platform supporting frame thereabove, of a platform formed of sheet metal provided with depending flanges

forming a skirt for enclosing the sides of said frame.

16. In a scale, the combination with an annular platform supporting frame, of a platform formed of sheet metal extending across said frame, a reinforcement for said platform secured to the under side thereof and extending across between the sides of said platform supporting frame, and a bearing on said platform supporting frame for engaging said cross bar and holding said platform from lateral displacement.

17. In a scale, the combination with an annular platform supporting frame, of a platform formed of sheet metal extending across said frame, a reinforcing bar secured to the under side of said platform and extending across said frame, and bearings on the opposite sides of said frame for engaging said cross bar and for retaining said platform from lateral displacement.

18. In a scale, the combination with a pedestal and an annular base frame to which said pedestal is attached, of a castor wheel rotatably mounted on said pedestal and enclosed within said annular frame.

19. In a scale, the combination with a pedestal and an annular frame on one end of which said pedestal is mounted, of a castor wheel within said annular frame directly rotatably mounted on said pedestal with clearance for swinging within the frame.

20. In a scale, the combination with an annular base frame, of a pedestal provided with a laterally extending foot flange mounted upon and covering a portion of said frame, and a castor wheel within said frame directly rotatably mounted on said foot flange on said pedestal.

21. In a scale, the combination with an annular base frame, of a pedestal having a laterally extending foot flange mounted upon and covering a portion of said base frame, and a pair of castor wheels directly rotatably mounted on said foot flange and enclosed within said annular frame with clearance for complete turning.

In testimony whereof I affix my signature.
WALTER F. STIMPSON.
